UNITED STATES PATENT OFFICE.

LLOYD C. GLISSON, OF NEW YORK, N. Y.

FIRE-EXTINGUISHER.

1,280,208.

Specification of Letters Patent.

Patented Oct. 1, 1918.

Application filed February 10, 1912. Serial No. 676,882.

To all whom it may concern:

Be it known that I, LLOYD C. GLISSON, citizen of the United States, residing at New York, in the county of New York and State 5 of New York, have invented certain new and useful Improvements in Fire-Extinguishers; and I do hereby declare the following to be a full, clear, and exact description of the invention, such as will enable others skilled in 10 the art to which it appertains to make and use the same.

This invention relates to fire extinguishing apparatus, and more particularly to that class wherein an initial pressure is provided 15 for forcing a fire extinguishing chemical on to a fire and an auxiliary reserve supply is provided for maintaining the operation in case the fire is of any considerable duration.

The principal object of my invention 20 is to provide an apparatus of the kind mentioned which shall be simple in construction and efficient and certain in operation.

An object of this invention is to provide 25 automatic means for forcing fire extinguishing chemical on to a fire such as carbon-tetrachlorid, such chemical not possessing any pressure producing qualities within 30 itself, and which may be operated by and in conjunction with a municipal or other water supply, or which may be operated without a water supply should such supply be shut off or not available.

A further object is to provide an automatic apparatus which may be operated 35 from a distant point, and which does not require the maintenance of air pressure in a piping system requiring constant attention to maintain the same in operative condition, and which does not require a mechanical 40 train with its necessary complications and other objectionable features.

Another object is to provide automatic means for shutting off the pressure supply 45 means when a fire has been extinguished, thus conserving the supply of chemicals and preventing the generation of unnecessarily high and dangerous pressure.

A further object is to provide automatic 50 means for generating pressure in proportion to the number of outlets or nozzles in operation.

A further object is to provide means for

preventing the chemical from mixing with the pressure supply means, thereby contaminating the pressure water supply means and 55 weakening the chemical supply.

A further object is to provide means for manually starting the operation of the apparatus in addition to the automatic means.

A further object is to provide an automatic mechanically operated alarm, which sounds in case of fire, or if the system or apparatus should ever require attention. This 60 overcomes the objections of the electrically operated alarm with its delicate mechanism 65 and its batteries which require constant attention.

Further advantages and features of this invention will be apparent from the accompanying specification, claims and drawing 70 showing an illustrative apparatus in a somewhat diagrammatic way and in which,—

The drawing is a sectional view through a device constructed in accordance with my invention.

In the drawing I have shown enough of an operative fire extinguishing apparatus to illustrate the principles embodied in the present invention, although without attempting to show the apparatus in all of its details of construction and arrangement in the exact form which it will have when installed 80 in buildings or other places and which may be connected to a stand-pipe or sprinkler system.

In order that the purposes and advantages 85 of the invention may be better understood, I desire to state, before going into a detailed description of the invention, that carbon-tetrachlorid is an instantaneous fire extinguishing agent, being efficient for extinguishing all kinds of fires, including especially gasoline, oils, and even electric arcs and is the most powerful fire extinguishing agent known therefor, being many times 90 as efficient as water and much more efficient for this purpose than the usual soda and acid solution. Carbon-tetrachlorid is a liquid that contains absolutely no moisture, it is non-freezing, it will not corrode the finest 100 machinery or damage the finest furniture or fabrics, and does not deteriorate with age. While only the chemical carried in the solution of the soda and acid apparatus is con-

verted into gas, the entire volume of carbon-tetrachlorid is converted into gas the instant that it is brought into contact with fire, which gas being much heavier than air, 5 displaces the oxygen containing air thereby stopping combustion; and when thrown on the base of a fire, it not only extinguishes the fire with which it comes into contact, but the gas is drawn into the flame by the draft 10 caused by the fire, thereby following the fire up and extinguishing it.

I desire to state further that it is not only important, but essential, that an automatic chemical fire apparatus, when once charged 15 and made ready for operation should remain in such condition for an extended period without requiring attention. This is practically impossible where an air pressure is maintained in a piping system, because it 20 requires absolute perfection to hold air pressure, and this is hard to attain in pipe-fitting, as the vibration and settling of buildings cause small leaks in a piping system, which with air passing therethrough gradually 25 become larger. On the other hand, it is a comparatively easy matter to make a piping system liquid tight, and especially so when the liquid is much heavier than water, and if a small leak should occur it tends to 30 "take up".

To accomplish the desired results in apparatus of the class above referred to, in addition to parts to be hereinafter described, I provide a container 10 and tank 11. Entering 35 the lower end of container 10 is a water supply pipe 12, which is provided with a nozzle 13, for the purpose of agitating and dissolving the soda placed in the bottom of container 10 and which pipe may be provided 40 with valve 14 for controlling the passage of water through said pipe. The valve and pipe 12 may be connected to a main supply pipe 15, which in most cases may be connected to a municipal water supply or pressure tank. 45

The container 10 is provided with hand hold 16, which is closed by cap 17, which opening permits the supplying of the several chemicals for charging. The outlet conduit 50 18 is provided with strainer 19 and check valve 20, and has connection with a cylinder 21. Connected to pipe 18 is branch pipe 22, which passes through the side of container 10 and is connected through check 55 valve 23 to the system supply conduit 24, which may be run throughout a building and may be provided at intervals with a valve 25 to which may be attached a hose 26, and automatic sprinklers 27. The cylinder 21 60 is connected adjacent to its upper end through check valve 28 to the supply conduit 24. The cylinder 21 has a check valve 21^a in the upper end thereof and loose piston 29 with its rod 30, which is loosely connected to an arm 31 of an acid receptacle 65

32 which is fulcrumed at 33 within the container 10, which acid receptacle has a restricted opening and is provided with a hinged cover 34, and is so designed that only one fourth of a revolution is required to 70 empty its entire contents. This acid receptacle may be of suitable construction such as is disclosed in my prior application, Serial No. 472,980, filed January 18, 1909, whereby a quantity of acid is first discharged 75 from the receptacle and thereafter a small continuing flow of acid is possible.

The tank 11 is adapted to contain a chemical in concentrated form, as for instance dry soda, which may be supplied through a hand hole, not shown. Within the tank 11 is a stationary acid receptacle 35 which is adapted to contain a solution of acid and water for the purpose of generating a large volume of free gas when discharged into the dry 80 soda, for the purpose of maintaining pressure in container 10 during operation, which will be more fully described hereafter. Connected to receptacle 35 and tank 11 is conduit or pipe 36, which may be provided 85 with check valves 37 and 38, said pipe forming a loop and being connected to supply pipe 15. The pipe 36 is further provided with means for operating an automatic mechanical alarm such as the casing 39 and a 90 float 40, which may be connected to an alarm or other mechanism through pipe 41. The pipe 36 is also provided with valve 42 for controlling the passage of fluid therethrough. 95

The receptacle 35 is provided with a siphon 100 comprising pipe 43 which terminates near the bottom thereof and rises above the solution contained therein and provides an opening into tank 11 as at 47. In connection with receptacle 35 there may be provided a 105 chamber or cylinder 44, containing a slideable member or sliding weight 45. This weight or member is to retard the acidulated water passing through and develop pressure in this water, so that it is brought forcibly into 110 contact with the soda and with force for the purpose of agitation. Connected to cylinder 44 at intervals are pipes 46, which pass through the wall of container 35, and extend down to different depths as shown at 115 47, for the purpose of causing the contents of receptacle 35 and the incoming water to be discharged at different elevations through the soda so as to form a gas and break up any mass of soda that may be 120 formed in the container and to produce agitation as the soda is being dissolved. The receptacle 35 is provided with a plunger 48, which passes through the top of the tank 11 and is provided with the usual gland 49 and 125 said plunger is further provided with a valve 50 in the upper end thereof so that the pressure in the receptacle may be relieved therethrough. The plunger is provided for the purpose of providing a manually operated 130

means for starting the operation of the apparatus, and the valve 50 is for relieving the pressure for re-charging.

The tank 11 has communication with the container 10 through the pipe 51 which extends downward to near the bottom of this container for the purpose of stirring and carbonating the chemical contained therein. The pipe 51 may have a check valve 52 communicating therewith above the solution in the container 10.

One mode of operating the apparatus is as follows. Tank 11 may be filled with chemical in concentrated form such as dry soda, to approximately the height shown by the dotted line therein. Then the receptacle 35 is filled with diluted acid, or acid and water, to approximately the height shown by the dotted line therein. For charging container 10, dry soda is placed in the container through hand-hole 16. The required amount of acid is placed in the receptacle 32. The piping system is then filled with a suitable liquid, as for instance carbon-tetrachlorid, a quantity of carbon-tetrachlorid may be placed in the container 10 also if desired. The cap 17 is then screwed on, then valve 14 is opened, which forcibly discharges water through nozzle 13 into the soda for dissolving the soda and impregnating the water therewith. The water being much lighter than the carbon-tetrachlorid it rises to the top and occupies the position indicated by dotted lines from B to C, the carbon-tetrachlorid occupying the position indicated by dotted lines from A to B, the incoming water compresses air in container 10, tank 11, and a portion of pipe 36 to check valve 37, the pressure passing from one to the other through check valves 52 and 38, which checks work in the direction indicated by the arrows. The air also passes through pipe 46, through cylinder or chamber 44, around member 45 and through the acid into the top of acid receptacle 35, thus establishing an equilibrium of pressure. Then valve 14 is closed and valve 42 is opened. The pipe 36 above the valve 42 is provided with a bleed valve 58 to drain said pipe when desired. The apparatus is then in operative condition and should remain in such a condition for an extended period. If a leak should occur the water in pipe 36 will rise, raising float 40, which allows water to pass through the pipe 41 to the alarm which gives warning that the system needs attention. When a fire occurs, a valve or sprinkler is opened allowing the fluid in the container 10 to be forced through the outlet pipe 18, check valve 20, through cylinder 21, raising piston 29; thereby tilting the acid receptacle 32 and starting the flow of acid into the alkaline solution, thus producing a high operating pressure. The pressure thus produced is transmitted to tank 11 receptacle 35

and a portion of pipe 36 to check valve 37, thereby establishing an equilibrium of pressure therein, in the manner previously described. If the fire is of short duration the outlet is closed, the piston 29 settles by gravity causing the acid receptacle 32 to resume its former position, thus stopping the flow of acid, and thereby stopping the generation of pressure. If however the discharge is of sufficiently long duration, the equilibrium of pressure between acid receptacle 35 and tank 11 is broken as soon as the pressure in conduit 24, container 10 and tank 11 begins to decrease, thereby causing the pressure in receptacle 35 to force acid therefrom in sufficient volume for generating pressure to compensate for the discharge of pressure from conduit 24 container 10 and tank 11, thus generating pressure in proportion to the size or number of outlets discharging from the outlet conduit. If the outlet or outlets are closed while the apparatus is in operation, the equilibrium is re-established in the manner previously stated, thus stopping the generation of pressure. On the other hand, if it is necessary to continue the operation of the apparatus for any considerable length of time the reserve supply automatically begins operation as soon as the pressure begins to decrease. The reduction of pressure in tank 11 allows the pressure in acid receptacle 35 to force a quantity of acid solution therefrom onto the dry soda thus forming a large quantity of free gas, which raises the pressure in the tank to or above that within the acid receptacle and stops the flow of acid, any excess pressure acting to increase the pressure in receptacle 35. The operation is repeated at intervals until practically all of the solution in receptacle 10 has been discharged, and the pressure reduced to the same amount as the water pressure in the supply pipe 15; then the water flows through the acid receptacle 35 into the soda, through one or more of the pipes 46, governed by the number of outlets or nozzles in operation. The weight 45 provides a pressure for controlling the water, and as previously stated, opens one or more of the outlets so that the water is admitted to the soda in a jet or jets to produce agitation.

Where a water supply is not available or desirable, the apparatus may be set in operation by gravity. After the distributing pipe 24 and the connected sprinkler lines are filled with extinguishing liquid in the customary way, and the container 10 charged with chemicals and sealed so that the air space at its top is at about atmospheric pressure, the liquid is sustained in the closed upper part of the distributing system by atmospheric pressure as in a barometer tube. If a valve or sprinkler is then opened below the level of the container the fluid in the pipe flows out by gravity and the siphoning ef-

fect raises the piston 29 thereby mixing the chemicals. If a valve is opened at a higher level than the container, thereby admitting air to the distributing pipe, the fluid in the pipe flows by gravity back into the container through check valve 23, raising the piston 29 and starting the operation. Check valve 21^a is provided for this purpose to allow the pressure from the system to raise the piston.

10. Where the water pressure is sufficiently high and constant to be relied upon, the acid and alkaline solution in container 10 may be omitted, and this container filled to dotted line C with carbon-tetrachlorid, which is far more efficient. In this case the carbonic acid gas which is generated in tank 11 flows through pipe 51 into the bottom of container 10, thereby carbonating the solution and increasing its efficiency. This pipe may be extended into the bed of chemical in powdered form in the bottom of container 10 thereby mixing said chemical with the solution therein and thereby further increasing its efficiency.

25. For operating the apparatus manually, the piston 48 is forced down, which operation forces a predetermined quantity of acid out of receptacle 35 to raise the pressure to the desired point. The acid then continues to feed automatically in the manner previously stated.

The term "siphon" is used herein as comprising a form or type of discharge conduit having an inlet end extending upward from the lower part of a vessel or container and to a point above the normal liquid level in said container and operated by a difference of head or pressure; and the term "pressure siphon" is used in referring to a siphon in which the container forms a closed receptacle in which the gaseous pressure around the inlet leg of the conduit is greater than the external pressure adjacent its discharge end.

It is obvious that the principles involved in the present invention are adaptable to a great variety of forms, modifications and uses for meeting various requirements, including small apparatus that may be carried around a building so that it does not necessarily involve an extensive system of piping to transmit the fire extinguishing fluid, and including dry pipe systems, either as pressure or vacuum systems, it being operable either by fluid flowing from the pressure generating apparatus to the distributing conduit or by fluid flowing from the distributing conduit to the pressure generating apparatus as previously described.

I claim:

60. 1. In a fire extinguishing apparatus, a container having an outlet, automatic means adapted to generate pressure upon the flow of liquid through said outlet and automatic means comprising a pressure operative

siphon adapted to maintain generation of pressure in proportion to the flow of liquid through said outlet.

2. A fire extinguishing apparatus comprising a tank having an inlet provided with an automatic sprinkler head and an acid receptacle in said tank having automatic pressure operative siphonic means adapted to be controlled by the flow of liquid through said outlet.

3. A chemical engine comprising a container, having a conduit with a plurality of outlets, means for generating pressure and automatic means for generating a secondary pressure in proportion to the number of outlets discharging from the conduit.

4. A chemical engine comprising primary means adapted to generate pressure and reserve supply means controlled thereby and adapted to generate and maintain a secondary pressure and comprising a pressure operative siphon.

5. A chemical engine comprising a container, having a conduit with a plurality of outlets, primary means for generating pressure, reserve supply means comprising chemicals to be mixed for generating a secondary pressure and automatic means for mixing the chemicals in proportion to the number of outlets discharging from the outlet conduit.

6. A fire-extinguishing apparatus, comprising a tank for a fire extinguishing chemical, an outlet conduit system having communication with said tank, a valve controlled water supply to said tank, an acid receptacle therein, said water supply entering said tank through said acid receptacle, to chemically treat the inflowing water and an alarm actuated by the ingress of water into said tank.

7. In a fire extinguishing apparatus, a tank, a conduit leading from said tank provided with a check valve, a stationary acid receptacle adapted to discharge acid into said tank, a return conduit operatively connected with said outlet conduit at opposite sides of the check valve, a check valve in the return conduit adapted to operate in reverse direction from the first named check valve and means controlled by flow through said conduits adapted in turns to influence said flow.

8. In a pressure generating apparatus comprising a tank having an outlet, an acid receptacle in said tank, and a valve controlled water supply to said acid receptacle, said acid receptacle communicating with said tank through a series of divided outlets of different elevations and a controlling means for exposing one or more of said outlets, said tank having a chemical in concentrated form and said receptacle having a dilute reagent solution.

9. A fire extinguishing apparatus comprising a sprinkler system, a container connected to said system and adapted to contain a quantity of chemical in solution, an auxiliary tank containing a reserve supply of the chemical in concentrated form in communication with the container, a water supply pipe having a plurality of outlets into the tank, and a weighted valve member, governed by the demand upon the apparatus for opening one or more of such outlets.

10. In a fire extinguishing apparatus, the combination with a container for a fire-extinguishing solution in its normal state, an auxiliary tank containing chemical in concentrated form, and means for supplying water to the tank as the solution therein is withdrawn, the said water supplying means being arranged to direct the water first into the auxiliary tank, whereby the incoming water is impregnated with the chemical.

11. In a fire extinguishing apparatus, the combination with a container for a chemical solution in its normal state, a tank containing concentrated chemical means for automatically supplying water to the tank to take the place of the solution withdrawn therefrom, and means for causing the water so supplied to be mixed with the chemical in proportion to the amount consumed whereby the strength of the solution is maintained.

12. In a fire extinguishing apparatus, the combination with a container for a chemical solution in its normal state, an auxiliary reservoir containing a quantity of a chemical in concentrated form and in communication with said container, and water supplying means controlled by the pressure in the container for replenishing the loss of solution therefrom, arranged to discharge first into the auxiliary reservoir, wherein it becomes impregnated with the chemical, and whence it flows into the container carrying the chemical in solution.

13. A chemical mixing fire extinguishing apparatus having a conduit, a stationary acid supply means in communication with said conduit, said conduit containing a body of air adjacent said acid supply means and pneumatically operative siphonic means adapted to be operated automatically under fire emergency conditions to discharge acid from said acid supply means.

14. A fire extinguishing apparatus comprising in combination a container adapted to contain a chemical solution under pressure and having an outlet to permit discharge of the solution, an acid receptacle in such container above the level of the solution and having an outlet, an auxiliary alkali tank connected with said container, a water supply conduit having a plurality of outlets into the tank through which water is caused to issue to replenish the solution

withdrawn from the container, a valve member movably mounted in said conduit displaceable by the water passing therefrom through distances proportional to the rate of flow of the water, whereby it is caused to open one or more of said outlets, to an extent proportional to the movement of said valve member.

15. In a fire extinguisher, a tank adapted to contain a quantity of soda, a receptacle communicating with said tank adapted to contain acid, said receptacle communicating with said tank from the bottom thereof through a conduit rising above the surface of the liquid in said receptacle and distributed through branched outlets depending to various elevations in said tank.

16. In a fire extinguishing apparatus comprising a container, having a conduit with a plurality of valved outlets, primary means for generating pressure, a reserve supply means adapted for generating pressure in proportion to the number of outlets discharging from the conduit, and automatic means operable by the opening of a valve for starting the generation of pressure.

17. A fire extinguisher comprising a container, an outlet conduit provided with a check valve leading from said container, a return conduit provided with a check valve operatively connected with said outlet conduit at opposite sides of said first named check valve, a cylinder in the outlet conduit between the first named check valve and the connection between the return conduit and the outlet conduit, a piston in said cylinder adapted to be operated by the flow of fluid in said conduits and means connected with said piston adapted to influence said flow.

18. A chemical mixing fire extinguishing apparatus comprising siphonic chemical mixing devices including a tank, an acid chamber containing pressure producing acid, a discharge chamber communicating with said acid chamber and with said tank and automatic pressure actuating means to cause the flow of acid from said acid chamber to said discharge chamber and thence into said tank.

19. A fire extinguishing apparatus comprising a container for a chemical fire extinguisher solution, a water supply conduit having a branch opening into and directed toward the bottom thereof for admitting water to charge the apparatus and arranged to stir the solution, and having a second branch having communication with the upper part of the apparatus for supplying water under pressure to expel the contents of the apparatus, and means for closing the first branch and opening the second when the apparatus has been charged.

20. A fire extinguishing apparatus com-

prising a chemical tank, an acid receptacle within said tank, said receptacle communicating with said tank from adjacent the bottom thereof to above the level of the liquid therein, a plunger acting in said receptacle to compress the air therein when so desired and a relief valve therein to relieve the pressure when so desired.

21. A chemical fire extinguishing apparatus comprising a chemical tank and a stationary receptacle containing pressure producing chemical, a chemical mixing siphon discharging chemical from said receptacle and having a discharge end lower than its inlet end and pneumatic actuating means to operate said siphon upon the discharge of liquid from said apparatus under fire extinguishing conditions.

22. In a fire extinguishing apparatus, a tank, an admission conduit for conducting water under pressure to said tank, said conduit rising to near the top of said tank above the normal level of liquid in the tank, an escape outlet in the conduit, a valve controlling said outlet, and automatic means for opening said valve to permit escape of water when the level in the conduit rises.

23. A fire extinguishing apparatus comprising a container charged with extinguishing liquid under pressure and having an air space above said liquid, an inlet conduit for supplying water under pressure to said container and having a portion extending above the liquid level in the container and having a discharge end below said water level and an auxiliary connection between said conduit and said container located above said liquid level and communicating with the air space above the liquid level in said container.

24. In a fire extinguishing apparatus, a tank for a chemical, an acid receptacle to discharge into said tank and a pipe connected to said acid receptacle to cause the ingress of water to be through said acid receptacle automatically.

25. A fire extinguishing apparatus comprising a tank, an outlet conduit to a distributing system from said tank, an acid receptacle conduit for admitting water under pressure through the bottom of said acid receptacle and an outlet from said acid receptacle in alignment with and terminating near said water inlet.

26. A fire extinguishing apparatus comprising a tank having an outlet, an inlet conduit for supplying water under pressure, said outlet being normally closed to maintain a normal pressure equal to the water supply, an acid receptacle communicating with said tank, said inlet conduit entering said acid receptacle, said inlet conduit having a return bend therein to normally hold a quantity of imprisoned and compressed air, an outlet from said inlet conduit before it

enters said acid receptacle, a float actuated valve for normally closing said outlet and said outlet permitting the discharge of any leakage due to conditions in or through said container.

70 27. A fire extinguisher comprising a tank having automatic siphonic chemical pressure generating means, including a stationary acid receptacle, adapted to be operated upon the movement of liquid to thereby generate pressure.

75 28. A chemical fire extinguishing apparatus comprising a distributing system having fire extinguishing distributing devices, a connected chemical tank and a stationary receptacle containing pressure producing chemical, a chemical mixing siphon, discharging chemical from said receptacle and having a discharge end lower than its inlet end and fluid actuating means to operate 80 said siphon upon the discharge of fluid from said apparatus under fire extinguishing conditions.

85 29. A chemical fire extinguishing apparatus comprising a fire extinguishing distributing device, connected chemical mixing pressure generating devices comprising a receptacle containing pressure producing chemical, a chemical mixing siphon to discharge chemical from said receptacle and having a discharge end lower than its inlet end, and means to start the operation of said siphon upon the fire emergency operation of said distributing device.

90 30. A fire extinguishing apparatus comprising a fire extinguishing distributing device and a connected pressure generating apparatus, a stationary receptacle communicating with said apparatus and containing pressure producing chemical, a discharge conduit 100 for said receptacle having an inlet end extending upward from the lower portion of said receptacle and above the normal level of the liquid therein and automatic means to discharge chemical through said conduit and 110 generate pressure by the mixture of chemicals on the fire emergency operation of said distributing device.

105 31. A fire extinguishing apparatus comprising a distributing system provided with 115 automatic sprinkler heads and a connected pressure generating apparatus including a receptacle containing pressure producing liquid, a discharge conduit for said receptacle having an inlet end extending upward 120 from the lower portion of said receptacle and above the normal level of the liquid therein and having a discharge end extending below said receptacle and means to discharge such pressure producing liquid 125 through said conduit and generate pressure by the mixture of chemicals on the fire emergency condition of one of said automatic sprinkler heads.

130 32. A fire extinguishing system comprising

- ing a chemical pressure generator, a pipe having normally open communication with said pressure generator and adapted to maintain said generator in operative condition by hydrostatic pressure in said pipe, means for maintaining a body of air between said generator and the liquid in said pipe and means for preventing free gas from said generator from discharging through said pipe.
33. A fire extinguisher comprising a chemical pressure generating apparatus, a conduit leading therefrom, a stationary acid receptacle having a discharge passage communicating with said pressure generating apparatus and extending upward from near the bottom of said acid receptacle to above the normal liquid level therein and means comprising an automatic sprinkler head adapted to cause the movement of liquid in said conduit and thereby discharge acid through said passage.
34. A fire extinguishing apparatus comprising a tank containing extinguishing liquid and provided with a normally closed fire extinguishing distributing device, a stationary receptacle charged with pressure producing chemical and communicating with said tank and automatic pneumatically operative means actuated on movement of fluid through said distributing device to discharge chemical into said tank and generate pressure therein.
35. A fire extinguishing apparatus comprising a closed tank containing extinguishing liquid and having a connected outlet conduit, communicating chemical mixing pressure generating devices comprising a receptacle charged with pressure producing chemical and a normally open siphon adapted to discharge chemical from said receptacle upon the movement of liquid in said conduit.
36. A fire extinguishing apparatus comprising a closed tank having an outlet conduit, a stationary acid receptacle and a siphon adapted to discharge acid from said acid receptacle into said tank upon the movement of liquid in said conduit.
37. In a fire extinguishing apparatus, a tank for a fire extinguishing chemical, an acid receptacle therein, a water supply to said tank and said water supply entering said tank through said acid receptacle.
38. A fire extinguishing apparatus comprising a closed tank provided with normally closed fire extinguishing distributing devices, a stationary acid supply means communicating therewith and provided with means adapted to operate automatically by pressure to effect the operation of said acid supply means upon the opening of a distributing device.
39. A fire extinguishing system comprising a distributing conduit, a container connected thereto and means operable by the flowing of liquid from said conduit to said container for increasing the pressure therein.
40. A fire extinguishing system comprising a distributing conduit, a container connected to said conduit, and means operable by the flow of liquid from said conduit to said container for increasing the pressure therein, and a valve in said conduit for controlling said flow of liquid.
41. A fire extinguishing apparatus comprising a closed chemical pressure tank provided with an outlet, a stationary acid receptacle connected thereto, and automatic pneumatically operative means adapted to be operated by movement of fluid through said outlet to cause acid to flow into said tank to generate pressure therein.
42. A fire extinguishing system comprising a distributing conduit, a chemical pressure generator having a stationary acid receptacle and a communicating operating piston and automatic means adapted to be operated by movement of fluid in said conduit to effect the operation of said generator.
43. A fire extinguishing apparatus comprising a closed tank having an outlet conduit, stationary acid supply means operatively connected therewith, means adapted to be operated automatically by the movement of fluid in said conduit to cause acid to flow into said tank and increase pressure therein.
44. A fire extinguishing system comprising a distributing conduit and automatic siphonic chemical mixing means operated by flow of fluid in said conduit to produce pressure therein.
45. A fire extinguishing system comprising a distributing conduit having fire extinguishing distributing devices, a stationary acid receptacle operatively connected therewith and siphonic chemical mixing means connected with said receptacle to discharge acid therefrom and increase the operating pressure in said conduit, said mixing means being adapted to operate upon the movement of fluid in said conduit when a distributing device opens.
46. A fire extinguishing system comprising a distributing conduit having fire extinguishing distributing devices and siphonic chemical mixing means to generate pressure and adapted to operate upon the opening of one of said distributing devices.
47. A fire extinguishing system comprising a distributing conduit having fire extinguishing distributing devices and siphonic chemical mixing means to regulate the discharge pressure for said conduit and adapted to operate upon the opening of a distributing device.
48. A fire extinguisher comprising a tank, a stationary acid receptacle associated with said tank, means adapted to operate by pres-

sure in said acid receptacle to discharge acid into said tank and means comprising a sprinkler head adapted to operate automatically to supply pressure to the acid receptacle.

5 49. A chemical mixing fire extinguisher comprising a tank, a stationary acid receptacle associated with said tank, means adapted to operate by pressure in said acid receptacle for mixing chemicals in proportion to the rate of discharge from the tank and means comprising a sprinkler head adapted to operate automatically to supply pressure to the acid receptacle.

10 50. A fire extinguishing apparatus comprising an automatic chemical mixing pressure generating engine having connected fire extinguishing discharge devices, a stationary acid supply means operatively connected with said engine, means adapted to 20 operate by a reduction of pressure external to said acid supply means to discharge acid therefrom and means adapted to operate by the opening of a discharge device to supply pressure to said acid supply means.

25 51. A fire apparatus comprising a container having an outlet conduit, a self returning piston in said conduit, said piston being movable by liquid passing through said conduit.

30 52. A fire extinguishing apparatus comprising a distributing system provided with distributing devices, a connected tank, a stationary acid receptacle operatively connected therewith and pneumatically operative means adapted to be operated by reduction of pressure external to said acid receptacle to expel acid therefrom.

35 53. A fire extinguishing apparatus comprising an outlet conduit, a tank, a stationary acid receptacle operatively connected therewith, pneumatically operative means adapted to be operated by reduction of pressure external to said acid receptacle to discharge acid therefrom and means adapted 45 to be operated by movement of fluid in said conduit to supply pressure to said acid receptacle.

40 54. A fire extinguishing apparatus comprising a distributing conduit having a plurality of valved outlets, a tank, a stationary acid receptacle communicating therewith, pneumatically operative means adapted to be operated by reduction of pressure external to said acid receptacle to generate pressure in proportion to the number or size of outlets discharging from the apparatus and means adapted to be operated automatically by movement of liquid incident to the opening of an outlet in said conduit to supply 55 pressure to said acid receptacle.

55 55. A fire extinguishing apparatus comprising a distributing conduit, chemical mixing pressure generating devices to supply extinguishing fluid to said conduit and

comprising a supply of pressure producing 65 chemical and a pneumatically operated discharging siphon to be operated when extinguishing fluid is discharged through said conduit.

60 56. A fire extinguishing apparatus comprising a distributing conduit provided with fire extinguishing distributing devices and connected chemical mixing pressure generating devices comprising siphonic means to effect the mixture of chemicals when one of 75 said distributing devices comes into fire emergency operation.

70 57. A fire extinguishing apparatus comprising a chemical tank and a distributing conduit having a fire extinguishing distributing device, a stationary receiver containing pressure producing chemical and siphonic discharge means therefor to increase and control pressure in said conduit, said 80 means being operated by the opening of said 85 distributing device.

75 58. A chemical mixing fire extinguishing apparatus having a conduit, a connected chemical mixing pressure producing device, including a stationary acid receptacle, 90 means to discharge acid from said receptacle and supply pressure to said conduit and connections with said conduit to control the operation of said means by the hydrostatic pressure in said conduit.

80 59. A chemical mixing fire extinguishing apparatus comprising a distributing system having sprinkler heads and a tank having an acid receptacle, a conduit communicating therewith through said acid receptacle, the communicating means including a pressure generating siphonic acid discharge device adapted to be controlled automatically by the opening of a sprinkler head.

85 60. An automatic chemical mixing fire extinguishing apparatus having a conduit, a stationary acid receptacle for said apparatus in communication with said conduit, said conduit including means adapted to maintain a body of air between said receptacle and the liquid in said conduit, and means adapted to operate by the movement of fluid in said conduit to generate pressure in the apparatus.

90 61. An automatic chemical mixing fire extinguishing apparatus having a conduit, a stationary acid receptacle in communication with said conduit, said conduit including means adapted to maintain a body of air between the liquid in said conduit and said acid receptacle and means adapted to maintain hydrostatic pressure in said conduit.

95 62. A pressure generating fire extinguishing apparatus having a conduit, a stationary acid supply means in communication with said conduit, said conduit including means adapted to maintain a body of air

- between the liquid in said conduit and said acid supply means and means adapted to operate by hydrostatic pressure to generate pressure in the apparatus.
- 5 63. A chemical mixing fire extinguishing apparatus having a conduit, a stationary acid supply means in communication with said conduit, said conduit including means adapted to maintain a body of air between the liquid in said conduit and said acid supply means and pneumatically operative siphonic means adapted to operate by hydrostatic pressure to effect the expulsion of acid from said acid supply means.
- 10 64. A fire extinguishing apparatus comprising chemical mixing pressure generating means including automatic devices adapted to start the mixing of chemicals and pneumatically operative siphonic means controlling the further mixing of chemicals in proportion to the demand upon the apparatus.
- 15 65. A fire extinguishing apparatus comprising chemical mixing pressure generating means, including automatic pneumatically operative siphonic devices adapted to start the mixing of chemicals and automatic hydro-pneumatic means adapted to effect the further mixture of chemicals in proportion to the demand upon the apparatus.
- 20 66. A fire extinguishing apparatus comprising chemical mixing pressure generating means, a connected outlet conduit provided with fire extinguishing distributing devices, automatic hydro-pneumatically operative means adapted to start the mixing of chemicals and automatic pneumatically operative siphonic means adapted to control the further mixing of chemicals in proportion to the demand upon the apparatus, said means being adapted to be controlled by the opening and closing of a distributing device.
- 25 67. The fire extinguishing apparatus comprising a tank, a conduit adapted to contain liquid, a stationary acid receptacle having siphonic connection with said tank, an air compartment at a higher level than the normal liquid level in said conduit, a communicating pipe between said acid receptacle and said air compartment and means adapted to unbalance the pressures in said tank and receptacle to effect the discharge of acid from said receptacle.
- 30 68. A fire extinguisher apparatus comprising a tank, an acid receptacle provided with a siphonic discharge passage, a conduit adapted to contain liquid and having communication with said acid receptacle, means adapted to maintain a body of air between the liquid in said conduit and said acid receptacle and means adapted to unbalance the pressures in said tank and receptacle to effect the discharge of acid from said receptacle.
- 35 69. A chemical mixing fire extinguisher comprising a tank, a stationary acid receptacle, a pipe having communication with said tank, means adapted to provide pneumatic communication between said pipe and said tank and means adapted to operate by the movement of liquid in said pipe to mix chemicals pneumatically.
- 40 70. A chemical mixing fire extinguishing system normally charged with extinguishing liquid and comprising a pressure generating apparatus, a conduit communicating therewith and adapted to maintain said apparatus in operative condition by hydrostatic pressure in said conduit, a stationary pressure producing chemical supply means communicating therewith and pneumatically operative means adapted to be operated by movement of liquid in said conduit to effect the operation of said chemical supply means.
- 45 71. A fire extinguisher comprising a container, an acid receptacle pivotally mounted within said container, a conduit extending from said container, a piston mounted within said conduit, said piston being operable in one direction by the flow of fluid through said conduit for the purpose of tilting said acid receptacle and operable in the other direction by gravity to return said acid receptacle to its normal position.
- 50 72. A fire extinguishing apparatus comprising chemical mixing pressure generating devices including an acid receptacle, a conduit, an operating piston and a co-operating cylinder communicating with said conduit, said piston being operated in one direction by the flow of fluid through said conduit to effect the discharge of acid from said receptacle and said piston being operable in the other direction by gravity.
- 55 73. A fire extinguishing apparatus comprising a distributing system normally charged with extinguishing liquid, connected chemical mixing pressure generating devices and siphonic means controlled by the movement of liquid in said distributing system to effect the operation of said pressure generating means.
- 60 74. A fire extinguishing apparatus comprising chemical mixing pressure generating devices including siphonic means adapted to start the generation of pressure and supplemental siphonic pressure generating means connected to said apparatus to operate in proportion to the demand upon the apparatus or the number or size of outlets discharging therefrom.
- 65 75. A fire extinguishing apparatus comprising a distributing system provided with fire extinguishing distributing devices and connected chemical mixing pressure generating means including siphonic devices having a controlling connection with said distrib

- uting system to be automatically put into operation and to have their action automatically stopped when the discharge of liquid from said system ceases or when the discharge pressure becomes ample.
76. A fire extinguishing apparatus comprising an outlet conduit, a tank, a stationary acid receptacle operatively connected therewith, pneumatically operative means including a siphon adapted to be operated by reduction of pressure external to said acid receptacle to discharge acid therefrom and means adapted to be operated by movement of fluid in said conduit to supply pressure to said acid receptacle.
77. A fire extinguishing apparatus comprising a distributing conduit having a plurality of valved outlets, a tank, a stationary acid receptacle communicating therewith, pneumatically operative means including a siphon adapted to be operated by reduction of pressure external to said acid receptacle to generate pressure in proportion to the number or size of outlets discharging from the apparatus and means adapted to be operated automatically by movement of liquid incident to the opening of an outlet in said conduit to supply pressure to said acid receptacle.
78. The chemical mixing fire extinguishing apparatus comprising a distributing system, a connected pressure generating chemical mixing device comprising two acid chambers, one of which is arranged to initially discharge its contents and siphonic means to subsequently discharge the contents of the other chamber and means communicating with said distributing system and operating upon movement of fluid therein to effect the discharge of the contents of said acid chambers.
79. A chemical mixing fire extinguishing apparatus comprising a distributing system normally under pressure, connected chemical mixing pressure generating devices comprising two chambers containing pressure producing chemical, one of which is arranged to discharge its contents subsequent to and by reason of the discharge of the other, siphonic means for effecting the discharge from one of said chambers and generate pressure by mixture of chemicals and means adapted to operate by movement of fluid in said distributing system to effect the operation of said chemical mixing pressure generating devices.
80. A chemical mixing pressure generating apparatus comprising two chambers adapted to contain pressure producing chemical, one of which is adapted to discharge subsequent to the other and having a discharge siphon to regulate and automatically control the discharge of chemical therefrom in accordance with pressure fluctuations.
81. In a chemical mixing fire extinguisher, a tank, a stationary acid chamber, a chamber within said acid chamber and having communication with the tank and means adapted to operate by movement of fluid upon a reduction of pressure in said inner chamber to cause the acid in the other chamber to flow into the reduced pressure chamber and thence into the tank.
82. In a chemical mixing fire extinguisher system, in combination, a generating apparatus, a system supply pipe connected thereto and an acid supply means associated with said apparatus comprising two chambers, one of which discharges initially into the apparatus and the other of which discharges subsequently to the first named chamber.
83. The fire extinguishing apparatus comprising a distributing system containing extinguishing liquid and provided with automatic sprinkler heads, connected chemical mixing pressure producing devices comprising a tank, a receiver containing pressure producing chemical and a siphon discharge passage from said receiver into said tank to automatically discharge pressure producing chemical from said receiver on reduction of pressure in said tank and chemical means to produce fire emergency discharge pressure in said tank.
84. The fire extinguishing apparatus comprising a distributing system, connected chemical mixing pressure producing devices comprising a tank, a receiver containing pressure producing chemical and a siphon discharge passage from said receiver into said tank to automatically discharge pressure producing chemical from said receiver on reduction of pressure in said tank and means to produce discharge pressure in said tank.
85. The fire extinguishing apparatus comprising a tank, a communicating acid chamber, a discharge chamber located above the normal liquid level in said acid chamber and communicating with said tank, and means adapted to operate pneumatically on variation of pressure to cause acid to flow from the acid chamber into the discharge chamber and into the tank.
86. The fire extinguishing apparatus comprising a distributing system and connected chemical mixing pressure generating devices including a stationary acid receptacle, a chamber operatively connected with said receptacle, a movable flow influencing member within said chamber and adapted to be moved by the movement of fluid incident to a reduction of pressure in the distributing system.
87. The fire extinguishing apparatus comprising a distributing system, connected chemical mixing pressure producing devices comprising a tank, a receiver containing

- pressure producing chemical and a discharge passage from said receiver into said tank to automatically discharge pressure producing chemical from said receiver on reduction of pressure in said tank and means to produce discharge pressure in said tank.
88. The fire extinguishing apparatus comprising a distributing system containing extinguishing liquid, connected chemical mixing pressure producing devices comprising a tank, a receiver containing acid and a siphon discharge passage from said receiver into said tank to automatically discharge acid from said receiver on reduction of pressure in said tank and means to produce discharge pressure in said tank.
89. The fire extinguishing apparatus comprising a distributing system provided with automatic sprinkler heads, connected chemical mixing pressure producing devices comprising a tank, a receiver containing pressure producing chemical and a siphon discharge passage from said receiver into said tank and having a discharge end below said receiver to automatically discharge pressure producing chemical from said receiver on reduction of pressure in said system and means to produce fire emergency discharge pressure in said tank.
90. The fire extinguishing apparatus comprising a distributing system, connected chemical mixing pressure producing devices comprising a tank, a receiver containing pressure producing chemical and a siphon discharge passage from said receiver into said tank and having a discharge end below said receiver to automatically discharge pressure producing chemical from said receiver on variation of pressure in said system.
91. The fire extinguishing apparatus comprising a generating tank, a stationary acid supply receiver operatively connected with said tank, a conduit, an air compartment communicating with said conduit above the normal liquid level therein, an air connection extending from said receiver and having communication with said air compartment and pneumatically operative means adapted to operate by the movement of fluid in said conduit to effect the discharge of acid from said receiver.
92. The fire extinguishing apparatus comprising a conduit, connected chemical mixing pressure generating apparatus including a stationary acid supply receiver and an air connection between said receiver and said conduit to effect the discharge of acid from said receiver on movement of fluid in said conduit.
93. The fire extinguishing apparatus comprising a conduit and automatic sprinkler distributing devices, connected chemical mixing pressure generating apparatus including a stationary receiver containing pressure producing chemical and having a siphon discharge passage, an air connection between said receiver and said conduit to effect the discharge of chemical through said siphon discharge passage on the opening of a sprinkler distributing device and valve means adapted to prevent the discharge of gas from said receiver to said conduit.
94. The fire extinguishing apparatus comprising a tank, communicating chemical mixing devices comprising an acid chamber, a chamber located above the normal liquid level of said acid chamber and pneumatically operated means adapted to operate automatically upon a variation of pressure in said aperture to cause acid to flow from one of said chambers to the other and into said tank.
95. The fire extinguishing apparatus comprising a tank, a communicating acid chamber, a supplemental acid chamber communicating with said acid chamber and pneumatically operative means adapted to operate on the discharge of fluid from said tank to discharge acid from said chambers into said tank.
96. The fire extinguishing apparatus comprising a distributing system and connected chemical mixing pressure generating devices including a stationary acid receptacle, a chamber operatively connected with said receptacle, a movable flow controlling member within said chamber and adapted to be moved by the movement of fluid incident to the operation of the apparatus.
97. The fire extinguishing apparatus comprising a conduit, connected chemical mixing pressure generating devices comprising a stationary acid supplying receiver, an air connection between said receiver and said conduit and pneumatically operative means adapted to operate upon the movement of fluid in said apparatus to discharge acid from said receiver and means adapted to prevent gas from discharging from said receiver into said conduit.
98. A chemical mixing fire extinguishing apparatus comprising chemical mixing pressure generating devices including a tank and two chambers connected therewith and containing pressure producing chemical, and means to effect the discharge of such chemical from one of said chambers subsequent to and by reason of the discharge from the other.
99. A chemical mixing fire extinguishing apparatus having a conduit, siphonic stationary acid supply means communicating with said conduit, means to maintain a body of air between said acid supply means and the outer portion of said conduit and automatic operating means to discharge acid from said acid supply means automatically under fire emergency conditions.
100. The fire extinguishing apparatus

comprising a tank, a communicating chemical chamber containing pressure producing chemical, a discharge chamber communicating with said chemical chamber and automatically operating means adapted to operate on the fire emergency condition of the apparatus to discharge chemical from said chambers into said tank.

101. In chemical fire extinguishing apparatus, a distributing system comprising fire extinguishing distributing devices, a gaseous pressure tank and coöperating chemical mixing devices comprising a chamber containing a charge of acid pressure producing chemical, a discharge siphon communicating with said chamber and operating connections controlled by said distributing system to automatically start said siphon on the fire emergency action of one of said distributing devices.

102. In chemical fire extinguishing apparatus, a distributing system comprising automatic fire extinguishing distributing devices, a gaseous pressure liquid supply tank and coöperating chemical mixing devices comprising a chamber containing a charge of pressure producing chemical, a discharge siphon communicating with said chamber and operating connections controlled by the fluid conditions in said distributing system to automatically start said siphon on the fire emergency action of said distributing devices.

103. In chemical fire extinguishing apparatus, a distributing system comprising fire extinguishing distributing devices, and pressure producing chemical mixing devices comprising a receiver containing a charge of pressure producing chemical, a discharge siphon communicating with said receiver and operating connections controlled by said distributing system to automatically start said siphon on the fire emergency action of said distributing devices.

104. In chemical fire extinguishing apparatus, a wet pipe distributing system comprising automatic fire extinguishing distributing devices, a gaseous pressure liquid supply tank and coöperating chemical mixing devices comprising a receiver containing a charge of pressure producing chemical, a discharge siphon communicating with said receiver and operating connections controlled by the fluid conditions in said distributing system to automatically start said siphon.

105. In chemical fire extinguishing apparatus, a wet pipe distributing system comprising fire extinguishing distributing devices, a gaseous pressure tank and coöperating chemical mixing devices comprising a chamber containing a charge of pressure producing chemical, a pressure siphon communicating with said chamber to discharge

chemical therefrom and generate pressure in said tank, and operating connections controlled by the fluid conditions in said distributing system to automatically start said siphon.

106. In chemical fire extinguishing apparatus, a distributing system comprising fire extinguishing distributing devices, a pressure liquid supply tank charged with extinguishing liquid and coöperating chemical mixing devices comprising a chemical receiver, an acid chamber, a communicating air pressure chamber and an acid siphon communicating with said acid chamber and with said receiver to discharge chemical therefrom and generate pressure in said tank and connections between said tank and said distributing system creating a pressure difference between said air chamber and the air space of said receiver on the emergency action of one of said distributing devices to automatically effect the discharge of acid from said siphon.

107. In chemical fire extinguishing apparatus, a distributing system comprising fire extinguishing distributing devices, a liquid supply tank charged with extinguishing liquid and chemical mixing devices coöperating with said supply tank and comprising a chemical chamber containing a charge of pressure producing chemical and normally having a substantially closed air space above said chemical, a pressure siphon communicating with said chemical chamber to discharge chemical therefrom and generate pressure in said tank and connections between said system, said tank and said chamber to automatically start said siphon.

108. In chemical fire extinguishing apparatus, a distributing system comprising automatic fire extinguishing distributing devices, a gaseous pressure liquid supply tank and coöperating chemical mixing devices comprising a chamber containing a charge of pressure producing chemical and normally having a substantially closed air space above said chemical, a discharging siphon communicating with said chamber and operating connections controlled by the fluid conditions in said distributing system to automatically start said siphon on the fire emergency action of said distributing devices.

109. In chemical fire extinguishing apparatus, a distributing system comprising fire extinguishing distributing devices, a liquid supply tank charged with extinguishing liquid and chemical mixing devices coöperating with said supply tank and comprising a chemical chamber containing a charge of pressure producing chemical and a substantially closed air chamber communicating with said chemical, a discharging siphon communicating with said chemical chamber

and connections between said system, said tank and said chamber to automatically start said siphon.

110. A fire extinguisher comprising a pressure generating apparatus, an outlet conduit leading upwardly therefrom, a check valve in said conduit allowing flow away from said generating apparatus, a supplementary conduit communicating with said outlet at opposite sides of said check valve, a check valve in said supplementary conduit preventing flow away from said generating apparatus, pressure maintaining means comprising a stationary acid receptacle operatively connected with said apparatus and means adapted to be operated by movement of liquid in said conduit to effect the operation of said generating apparatus and pressure maintaining means.
111. A fire extinguisher comprising a pressure generating apparatus, a liquid filled outlet conduit leading upwardly and downwardly therefrom, and provided with fire extinguishing distributing devices, a check valve in said conduit allowing flow toward said distributing devices, a supplementary conduit communicating with said outlet at opposite sides of said check valve, a check valve in said supplementary conduit preventing flow toward said distributing devices, and chemical mixing means adapted to operate by the gravity induced movement of liquid in said outlet conduit at a higher or lower level than said apparatus to produce pressure therein.

112. A fire extinguisher comprising a pressure generating apparatus, a liquid containing outlet conduit leading upwardly and downwardly therefrom, and provided with fire extinguishing distributing devices, a check valve in said conduit allowing flow toward said distributing devices, a supplementary conduit communicating with said outlet conduit at opposite sides of said check valve, a check valve in said supplementary conduit preventing flow toward said distributing devices, and means adapted to operate by the gravity induced movement of liquid in said outlet conduit at a higher or lower level than said apparatus to produce pressure therein.

113. A fire extinguisher comprising chemical mixing pressure generating apparatus, including a tank containing extinguishing liquid, an outlet conduit leading downwardly therefrom, and provided with fire extinguishing distributing devices including automatic sprinkler heads and chemical mixing means adjacent said tank and actuated by the gravity movement of liquid in said outlet conduit when one of said distributing devices comes into fire extinguishing discharging condition to effect the operation of said pressure generating apparatus.

114. A fire extinguisher comprising chemical mixing pressure generating apparatus, an outlet conduit leading downwardly therefrom, and provided with fire extinguishing distributing devices and chemical mixing means actuated by the gravity movement of liquid in said outlet conduit when one of said distributing devices comes into fire extinguishing discharging condition to effect the operation of said pressure generating apparatus.

115. A fire extinguisher comprising chemical mixing pressure generating apparatus, a connected downwardly extending distributing system containing extinguishing liquid and provided with fire extinguishing distributing devices, and means actuated by the gravity movement of liquid in said distributing system when one of said distributing devices comes into operating condition to effect the operation of said pressure generating apparatus.

116. A fire extinguisher comprising chemical pressure generating apparatus, a connected downwardly extending distributing system containing extinguishing liquid and provided with fire extinguishing distributing devices, and means actuated by the gravity movement of liquid when one of said distributing devices comes into operating condition to effect the operation of said pressure generating apparatus.

117. A fire extinguisher comprising chemical mixing pressure generating apparatus, a connected upwardly extending distributing system containing extinguishing liquid and provided with fire extinguishing distributing devices, and means actuated by the gravity movement of liquid in said distributing system when one of said distributing devices comes into operating condition to effect the operation of said pressure generating apparatus.

118. A fire extinguisher comprising a chemical mixing pressure generating tank, a connected upwardly extending outlet conduit containing extinguishing liquid and provided with fire extinguishing distributing devices, and means actuated by the gravity induced movement of liquid in said outlet conduit when one of said distributing devices comes into operating condition to effect the operation of said pressure generating tank.

119. A fire extinguisher comprising a chemical mixing pressure generating tank, a connected outlet conduit containing extinguishing liquid and provided with fire extinguishing distributing devices, and means actuated by the gravity movement of liquid in said outlet conduit when one of said distributing devices comes into operating condition to effect the operation of said pressure generating tank.

120. A fire extinguisher comprising a distributing system having fire extinguishing distributing devices and containing extinguishing liquid and having considerable vertical extent, connected chemical mixing pressure generating apparatus, and means actuated by the gravity promoted movement of liquid in said distributing system when one of said distributing devices comes into operating condition to effect the operation of said pressure generating apparatus.

121. A fire extinguisher comprising a distributing system containing extinguishing

liquid and having considerable vertical extent, connected chemical mixing pressure generating apparatus, and means actuated by the gravity promoted movement of liquid in said distributing system to effect the operation of said pressure generating apparatus.

In testimony whereof I affix my signature in presence of two witnesses.

LLOYD C. GLISSON.
